(57) **CLAIM**

The ornamental design for a confection display package, as shown and described.

DESCRIPTION

FIG. 1 is a perspective view of a confection display package, showing our new design;

FIG. 2 is a front elevation view thereof;

FIG. 3 is a right side elevation view thereof, the left side elevation view being a mirror image thereof; and,

FIG. 4 is a top plan view thereof.

The bottom and back views of the confection display package form no part of the claimed design.
